UNITED STATES PATENT OFFICE.

JOHN M. DEWEY, OF SHELL ROCK, IOWA.

STOCK-WATERER.

SPECIFICATION forming part of Letters Patent No. 352,047, dated November 2, 1886.

Application filed September 2, 1886. Serial No. 212,535. (No model.)

To all whom it may concern:

Be it known that I, JOHN M. DEWEY, a citizen of the United States, residing at Shell Rock, in the county of Butler and State of Iowa, have 5 invented certain new and useful Improvements in Stock-Waterers; and I do declare the following to be a full, clear, and exact description of the invention, such as will enable others skilled in the art to which it appertains to 10 make and use the same, reference being had to the accompanying drawings, and to letters or figures of reference marked thereon, which form a part of this specification.

Figure 1 of the drawings is a representation 15 of a plan view. Fig. 2 is a vertical section on line *xx*, Fig. 1. Fig. 3 is a transverse vertical section on line *yy*, Fig. 1.

My invention relates to devices for watering stock; and it consists in the construction and 20 novel combination of parts, as hereinafter described, and pointed out in the claim.

Referring by letter to the accompanying drawings, A designates the main portion of the body of the stock-waterer, which is covered by an angular-hinged lid or cover, B, which, when closed down, extends over the top of the portion A of the body and down along the vertical edges of the ends C C' of 25 said main portion A, and meets the front upper edge, D, of said main portion. The auxiliary portion E of the body A, or that portion 30 of the device from which the stock drinks, is open at the top, in order that the stock may have ready access to the same.

Within the main portion A of the body I provide the feed-controlling receptacle or box F, which is connected below its bottom by the vertical rods or arms G G', secured to its opposite sides at its vertical middle line to the ends 35 of the curved diverging arms H H' of the lever I, said arms H H' having fulcrum-bends J in them, which bends rest upon a transverse rod, K, secured in the side walls of the box A.

Made integral with the curved arms H H' is 40 the weight-supporting arm L, which extends nearly to the vertical partition N, and this arm L, which is an open or slotted arm, is provided with an adjustable weight, P, which is 45 provided with a thumb-nut, Q, by which said 50 adjustable weight may be secured at any desired point, so that when there is no water

in the receptacle F the weight will descend and raise the receptacle F, which is connected through its bail R with the lower end of an angle-arm, S, the upper end of said angle-arm 55 S being fulcrumed in bearings T, projecting from the inner face of the end C' of the portion A of the body. This portion A is provided in its end C' with a supply-pipe, U, which is connected with the pump or tank which supplies the water to the stock-waterer, and the angle-arm S is provided with a stem-valve, V, which automatically closes the pipe U when the weight of the water in the receptacle F is sufficient to overcome the adjustable weight P on 60 the slotted arm L.

The receptacle F is connected by a flexible tube, W, with the box portion E, so that the water is conveyed through said pipe or tube W into the drinking receptacle or box portion 65 E. This construction provides for the automatic operation of the feed-controlling receptacle F; for as soon as the water in said receptacle F has run off into the drinking-receptacle E the weight will automatically open the 70 valve at the supply-pipe and permit the water to flow into the receptacle F until the weight of the water therein is sufficient to again close the valve. When the drinking-receptacle has been filled to the level of the flexible tube, the 75 device will cease to be operative until enough of the water in the drinking-receptacle has been consumed to bring the level of the water in the latter below the discharge end of the flexible tube, when the feed-controlling receptacle will again become operative. The back-water, which accumulates in the receptacle F after the drinking-receptacle is filled to the proper level, overcomes the adjustable weight 80 and closes the valve at the feed-pipe, which 85 will remain closed until the water can again run into the partially-exhausted drinking-receptacle, and in this way the drinking-receptacle will always have a supply of water there- 90 in for the stock so long as the supply at the tank or pump is kept up.

Having described this invention, what I claim, and desire to secure by Letters Patent, is—

The combination, with the main body por- 100 tion provided with the hinged cover and the open drinking-receptacle separated from the

main body portion by a vertical partition, of the feed-receptacle suspended through its bail from the lower end of the pivoted angle-lever, supported at its upper end in bearings projecting inwardly from the end wall of the main body portion, and provided with the stem-valve for closing the supply-pipe, and the weighted slotted lever fulcrumed on a transverse rod below the feed-receptacle and connected to the lower ends of the vertical arms

of the bail of said feed-receptacle, and the flexible tube connecting the feed-receptacle with the drinking-receptacle, substantially as specified.

In testimony whereof I affix my signature in presence of two witnesses.

JOHN M. DEWEY.
